US00D816711S

(12) **United States Design Patent** (10) **Patent No.:** **US D816,711 S**
Turner (45) **Date of Patent:** **** May 1, 2018**

(54) **DISPLAY SCREEN WITH COMPUTER ICON**

(71) Applicant: **Ultra Group USA, Inc.**, Norcross, GA (US)

(72) Inventor: **Sherman Turner**, Norcross, GA (US)

(73) Assignee: **Ultra Group USA, Inc.**, Norcross, GA (US)

(**) Term: **15 Years**

(21) Appl. No.: **29/609,272**

(22) Filed: **Jun. 29, 2017**

Related U.S. Application Data

(62) Division of application No. 29/547,231, filed on Dec. 2, 2015, now Pat. No. Des. 792,456.
